UNITED STATES PATENT OFFICE.

ALEXANDER L. SCHRAM, OF HILLSBORO, ILLINOIS, ASSIGNOR TO SCHRAM GLASS MFG. CO., OF ST. LOUIS, MISSOURI, A CORPORATION OF MISSOURI.

FRUIT-JAR.

1,353,278.

Specification of Letters Patent. Patented Sept. 21, 1920.

Application filed June 14, 1919. Serial No. 304,168.

To all whom it may concern:

Be it known that I, ALEXANDER L. SCHRAM, a citizen of the United States, and resident of Hillsboro, Montgomery county, Illinois, have invented certain new and useful Improvements in Fruit-Jars, of which the following is a specification containing a full, clear, and exact description, reference being had to the accompanying drawings, forming a part hereof.

This invention relates to certain new and useful improvements in fruit jars and has for its primary object a fruit jar provided with a lid receiving flange and a gasket flange around its mouth; a pair of bosses diametrically opposite each other and a clamping means pivotally and slidably mounted in the bosses.

A further object is to construct a fruit jar which has a wire clamping means, this clamping means being pivotally and slidably secured to the jar, the sliding feature of this pivot part is that it gives additional throw to the wire which fits over the jar top and in this way a shorter arm or throw can be used, or in other words, a small amount of wire saved on each trimming which in the aggregate will amount to a considerable saving in cost and material.

In the drawings:

Figure 1 is a side elevation of my device showing the clamping means in locked position on the jar and showing the clamping means released by dotted lines.

Fig. 2 is a fragmental view of the upper portion of a jar with the clamping mechanism removed.

Fig. 3 is an enlarged sectional view taken through one of the bosses and showing a portion of the clamping means secured therein.

In the construction of my device, I provide a jar having a body portion 4 and a neck 5, the neck 5 having around its upper end or mouth an upwardly projecting flange 6 which acts as a guide for the lid 7 and an outwardly extending flange 8 which acts as a support for the jar rubber or gasket 9. The neck 5 is further provided with a rib 10 and a pair of bosses 11. These bosses are formed integral with the neck and diametrically opposite each other.

The rib 10 extends around the neck and is formed integral therewith as well as with

the bosses. Its object is to prevent strain in the neck of the jar when it is molded.

The bosses are further provided with a recess or depression 12 which serves as a bearing for the ends 13 of the lever wire 14. This lever wire is substantially U-shaped. Adjacent each end of the lever wire, I form the eyes 15 which receive the inturned ends 16 of the lid clamping wire 17.

The recess 12 is practically semicircular in form (see Figs. 2 and 3) so that the surface 18 will form a sliding bearing point for the end 13 of the lever wire 14.

The lid 7 is provided with a central boss 19 and a pair of ribs 20. These ribs extend slightly above the top surface of the boss 19, their adjacent ends forming a recess 21 in which the clamping wire is adapted to fit and prevent its movement or shifting when the lid is clamped down.

As will be noted the ends 13 of the lever wire shift back and forth in the recess 12 (see solid and dotted positions of clamping means in Fig. 1) when the lid is clamped or released. This gives a much smoother and easier operating device than when a circular recess is used. The horizontal surface 18 of the recess 12 eliminates any tendency of the end 13 from becoming dislodged when strain is put thereon due to the clamping of the lid.

It will be observed that the peculiar shaped recesses in the bosses permit retaining considerably more material above the pivot points of the lever wire than below, this being advantageous for the reason that when clamping the lid, the strain on the ends 13 of the lever wire is upward and against the horizontal surface 18, this additional material obviating the tendency of that portion of the boss to chip or break out.

Encircling the flange 6 and adjacent the flange 8 is a gasket retaining recess 8'. The object of this is to hold the inner edge of the gasket in position on the flange and also to prevent it from lifting with the lid, and prevent the gasket from dropping off the jar when the lid has been removed.

The results will also be noted from Fig. 1 that when the lid is clamped, the ends 16 of the wire 17 are off center, that is, they extend past the center of the jar and therefore past the ends 13 of the lever wire, and

when any upward pressure takes place in the jar, the wire 17 will have a tendency to pull the lever wire 14 downwardly instead of raising it up, were the ends 16 on the opposite side of the ends 13, in which case the lever wire 14 would be raised and release the top or lid.

Having fully described my invention, what I claim is:

10. 1. A fruit jar comprising a body and a reduced neck portion, the neck portion being provided with a lid receiving shoulder and a gasket retaining recess, a rib formed integral with the neck portion substantially midway between the body of the jar and the lid receiving flange, bosses formed on the opposite sides of the neck portion and integral with the rib surrounding the neck portion, recesses formed in the bosses provided on their top with substantially flat horizontal upper walls, a lid clamping wire having its ends inturned and seated in said recesses, so as to provide shifting pivot points for said wire, a lever wire, and an eccentric connection between the lid clamping wire and the lever wire.
15. 2. A fruit jar comprising a body and a reduced neck portion, the neck portion being provided at its upper edge with a lid receiving shoulder, a gasket retaining recess formed around said shoulder, a second shoulder formed adjacent the gasket retaining recess and adapted to support the gasket, a rib formed integral with the neck portion substantially midway between the body of the jar and the lid receiving flange, a pair of bosses diametrically opposed formed integral with the neck portion and the rib, semi-circular recesses formed in the bosses
